UNITED STATES PATENT OFFICE.

GEORGE HENRY LINE, OF CHICAGO, ILLINOIS.

MONOGRAM-PANEL.

1,014,312.

Specification of Letters Patent.

Patented Jan. 9, 1912.

Application filed April 4, 1911. Serial No. 618,934.

To all whom it may concern:

Be it known that I, GEORGE H. LINE, a subject of the King of England, and a resident of the city of Chicago, county of Cook, 5 and State of Illinois, have invented certain new and useful Improvements in Monogram-Panels, of which the following is a specification.

My invention relates to improvements in 10 monogram panels designed for the ornamentation of doors, pianos, chiffonniers and other articles of furniture, the object of the invention being to produce a panel of this character which shall be of simple construction and artistic in appearance.

A further object of my invention is to so 15 construct the panel that the monogram may be removably inserted therein, thus affording means for changing the same when desired.

Other objects will appear hereinafter.

With these objects in view, my invention 20 consists in the novel construction and arrangement of parts all as will be fully described and more particularly pointed out in the appended claim.

My invention will be more readily understood by reference to the accompanying drawing forming a part of this specification 25 and in which,

Figure 1 is a front elevation of a panel embodying my invention, and Fig. 2 is a central longitudinal section thereof.

The preferred form of construction of my 30 invention as illustrated in the accompanying drawing comprises an elongated metallic panel 1 which may be of the form shown in Fig. 1 or any other similar elongated form. A series of figures 2 are inserted in the panel 40 1, the thickness of the figures being the same as that of the panel, but the color thereof preferably different in order to present a suitable contrast. The figures 2 are soldered into openings in panel 1 which correspond 45 in size with the figures, the sections of the latter being as illustrated in Fig. 2. Adjacent the upper end of the panel 1 a circular opening 3 is provided, a circular flange 4 projecting into the opening as illustrated in 50 Fig. 2. The flange 4 serves as a seat or stop for a monogram 5 which is inserted in the opening 3 and formed similar thereto. In order to retain the monogram 5 in the opening 3 after it has been positioned therein, 55 a series of wire tangs 6 are provided which extend from the periphery of the mono-

gram in a direction as indicated by dotted lines in Fig. 2. These tangs are formed of soft pliable metal so that after the monogram is positioned they may be bent into a 60 plane parallel with the body of the monogram, thus holding the same in position. After the tangs 6 have been bent as stated, they will assume the dotted line radial position as illustrated in Fig. 1, and be disposed 65 in the rear of the panel 1. It is now apparent that when the panel 1 is screwed to a surface 7 that the tangs 3 will be locked in position and that it will be impossible to remove the monogram 5 without detaching 70 the entire panel from said surface. The monogram 5 may have any design in the letters thereof, but it is essential that the periphery shall have a form as shown in order that the tangs 6 shall be suitably supported. 75 It is advantageous that the bars of each letter of the monogram be intertwined or interlocked with the bars of the other letter or letters composing the monogram in order that they shall be mutually supported and 80 be capable of standing any strain imposed thereon. In case that it is deemed desirable to change the monogram or to remove it for any reason from the panel, the screws by means of which the panel is secured to the 85 surface 7 are first removed and then the tangs 6 bent to their original position as shown by dotted lines in Fig. 2. The monogram may be now freely removed and another inserted in its place and thereupon 90 the panel 1 be again secured to the surface 7.

From the foregoing description it is clear that the panel 1 serves as an efficient monogram holder and that the monogram is securely locked in position in an expeditious 95 manner.

A monogram and panel of the construction set forth presents a neat appearance when attached to doors and articles of furniture, and due to the ease with which the 100 monogram may be inserted and removed, the device is particularly useful for the purpose for which it is designed.

While I have illustrated and described the preferred form of construction for 105 carrying my invention into effect, this is capable of variation and modification within the scope of the appended claim without departing from the spirit of the invention. I therefore do not wish to be limited to the 110 precise details of construction as set forth, but desire to avail myself of such variations

and modifications as come within the scope of the appended claim.

Having described my invention what I claim as new and desire to secure by Letters 5 Patent is:

The combination with a supporting member of a panel having an opening therein; a supporting flange at the bottom of said opening; a monogram fitted into said opening and resting on said flange; pliable projections on said monogram adapted to pass through said opening and be bent outwardly

against the back of said panel; and means for securing said panel to said support with said projections imprisoned between the rear 15 of said panel and the surface of said support, substantially as described.

In testimony whereof I have signed my name to this specification in the presence of two subscribing witnesses.

GEORGE HENRY LINE.
